UNITED STATES PATENT OFFICE.

MAURICE GANDY, OF LIVERPOOL, COUNTY OF LANCASTER, ENGLAND.

STRETCHING BELTING AND APPARATUS THEREFOR.

SPECIFICATION forming part of Letters Patent No. 269,519, dated December 26, 1882.

Application filed November 4, 1881. (No model.) Patented in Victoria October 4, 1880, No. 2,904; in India February 26, 1881, No. 565; in New South Wales March 28, 1881, No. 919, and in Norway June 7, 1881, No. 763.

To all whom it may concern:

Be it known that I, MAURICE GANDY, a subject of the Queen of Great Britain, and a resident of the city of Liverpool, in the county of Lancaster, in that part of the United Kingdom of Great Britain and Ireland called England, manufacturer of cotton belting, have invented certain new and useful Improvements in Stretching Cotton-Canvas and other Machine Belts and Apparatus Therefor; and the following is a full, clear, and exact description of my invention in such full, clear, and exact terms as to enable any one skilled in the art to which it appertains or is most nearly connected to make and use the same, reference being had to the sheets of drawings annexed to this specification, and to the figures of reference marked thereon.

My invention has for its object the nullifying or killing of the elasticity of machine-belts, more especially cotton-canvas belts constructed of cloths stitched together and saturated, as patented to me in the United States of America 1st day of June, 1880, No. 228,186, and is particularly applicable to the heavier class of belts and main drivers.

I have found by experience that the only way to effectually kill the elasticity of the heavier types of belts—such as main drivers—consists in the periodical taking up of the belt, and as this entails the undoing of and destruction of the lacing or fastening, and thereby weakens the belt, it is open to grave objections, and my present invention is essentially to avoid the necessity of this taking up by performing a similar operation prior to the application and use of the belt.

To effect the object of my invention, I use the device which is illustrated in sectional elevation in Figures 1 and 2, Fig. 2 being a continuation of Fig. 1. Fig. 3 is an end view of Figs. 1 and 2. Fig. 4 is a plan showing my method of attaching the ends and taking up the slack.

On reference it will be seen that the device or apparatus consists of a frame-work, A, on the ends of which are mounted a series of rollers, E E E E, free to revolve on their axis. The belts under treatment are represented by B, and it will be seen that two methods of operation are represented—namely, the upper

one shows the ends of the belt B connected together by the taking-up device F, and the under one shows one end of the belt B connected to a roller by a clamp, H, and the other end of the belt connected to another roller by a taking-up device, F, and the connection J.

It will be seen that the belt is stretched and its elasticity killed under precisely the same conditions that it would be subjected to when in use—namely, the whole length simultaneously exposed to strain, which is applied through the device F, which consists of the screw-rod K, revolving by means of the nut b within the link a. It will thus be seen that hour by hour, day by day, as the belt gives by the drying operation and by the strain to which it is exposed, the belt can be taken up and its elasticity practically exhausted.

The method of attaching the device F or the devices H J to the ends of the belt B is illustrated in detail at Fig. 4, and consists of the plates e or f, which hold the belt between them, as in jaws, and are attached to the belt by bolts and nuts, stitching, lacing, or other convenient method.

It will be seen that the apparatus subjects the belt to a continuous stretching operation which practically kills the elasticity.

I claim as my invention and desire to secure by Letters Patent—

1. The method substantially herein described of stretching belts, which method consists of first opening the belt through its entire length, of then stretching it over two or more rollers 85 and connecting the ends by a suitable stretching device, and of then applying tensile strain to its two ends and increasing it from time to time until the elasticity of the belt is exhausted, substantially as described.

2. The means substantially herein described of stretching belts, which means consists of the combination, with the two ends of a belt, B, of a taking-up device, F, and two or more rollers, E, set in a frame, A, the whole coacting, substantially as described, for the purpose specified.

MAURICE GANDY.
